(57) **CLAIM**

The ornamental design for an adjustable shelf assembly, as
shown and described.

DESCRIPTION

The design of this invention is embedded in an adjustable
shelf for stacking assembly utilized for storage.

FIG. 1 is a perspective view of adjustable shelf assembly.

FIG. 2 is a front view thereof; and,

FIG. 3 is an enlarged cross sectional view of one of the four
pillars shown in FIGS. 1 and 2.

The broken lines shown are for illustrative purposes only
and form no part of the claimed design.

1 Claim, 3 Drawing Sheets

FIG. 1

FIG. 2

FIG. 3
